(57) **CLAIM**

The ornamental design for a support stand, as shown and described.

DESCRIPTION

FIG. 1 is a front perspective view of a support stand showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

FIG. 8 is a front, perspective view of the support stand of FIG. 1 with additional environmental subject matter shown in broken lines;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The features shown in broken lines are portions of the support stand or environmental subject matter to the support stand forming no part of the claimed design.

1 Claim, 14 Drawing Sheets
